UNITED STATES PATENT OFFICE.

THEODORE RECTANUS, OF LOUISVILLE, KENTUCKY.

DESIGN FOR A CIGAR-LIGHTER CASE.

SPECIFICATION forming part of Design No. 20,080, dated August 5, 1890.

Application filed June 7, 1890. Serial No. 354,644. Term of patent 7 years.

To all whom it may concern:

Be it known that I, THEODORE RECTANUS, a citizen of the United States, and a resident of Louisville, in the county of Jefferson and State 5 of Kentucky, have invented a certain new and useful Design for Cigar-Lighter Cases; and I do declare the following to be a full, clear, and exact description of the invention, such as will enable others skilled in the art to which it applies to make and use the same, reference being had to the accompanying drawing, and to letters of reference marked thereon, which form a part of this specification.

The drawing is a representation of this design, and is a perspective view.

This design relates to a combined cigar-lighter and clock-frame; and it consists in the novel form and configuration of the parts, as shown and described.

20 In the annexed drawing, the letter A designates the rectangular case, the face of which in its lower portion is provided with a clock-dial, as at B. At each side of this lower portion are vertically-elongated receptacles C, of 25 cylindrical form. The incasement is verti-

cally extended above the level of the tops of the receptacles C and above the clock-dial, as shown at D. The top of the incasement is inclined upward from its outer edge inward to the wick E of a lamp F, which is provided 30 with a globe G, surmounting said lamp and incasement. The lower portion of the incasement is provided with a base H, which is extended outward on each side beyond the outer vertical limits of the side receptacles C, and 35 is beveled around its outer edge, as indicated at m. In this manner it is designed to provide a graceful design for a combined cigar-lighter and clock-case.

Having described this invention, what I 40 claim, and desire to secure by Letters Patent, is—

The design for a cigar-lighter case herein shown and described.

In testimony whereof I affix my signature in 45 presence of two witnesses.

THEO. RECTANUS.
